UNITED STATES PATENT OFFICE

2,468,024

RAILWAY TRACK SWITCH OPERATING MEANS

Marvin E. Blythe, Denver, Colo., assignor of fifty-five percent to Eva E. Blythe, Denver, Colo.

Application June 5, 1947, Serial No. 752,604

3 Claims. (Cl. 246—291)

1

This invention relates to railway switches, and has particular reference to novel means for yieldingly pressing the switch points into contact with the associated rails and to permit them to yieldingly separate from said rails, so as to avoid damage to the switch or derailing of a locomotive or train in case such locomotive or train should run through the switch when the latter is set against said locomotive or train.

A further object of the invention is to provide means of the above kind which is comparatively simple in construction, efficient in operation and easy to install.

The exact nature of the present invention, as well as more specific objects and features thereof, will become apparent from the following description when considered in connection with the accompanying drawings, in which:

Figure 1 is a fragmentary top plan view, showing an embodiment of the present invention, operatively associated with the rails and switch points of a railway.

Figure 2 is a transverse section taken on line 2—2 of Figure 1.

Figure 3 is a central vertical sectional view taken longitudinally through the double acting spring device forming part of the invention shown in Figures 1 and 2.

Figure 4 is a perspective view of the device shown in Figure 3.

Figure 5 is a transverse section taken on line 5—5 of Figure 3.

Figure 6 is an enlarged transverse sectional view taken on line 6—6 of Figure 3.

Referring to the drawings in detail, the rails 5 and 6 are laid in the usual manner upon cross-ties 7, and associated with these rails are switch points 8 and 9. As usual, the main track is completed when the switch point 8 is pressed against the rail 5, and the side track is completed when the switch point 9 is pressed against the rail 6. Manually operable means is provided to throw the switch points from either position to the other and to lock the same in either position. Such means includes a suitable actuating and locking device A mounted beside the switch and including a reciprocable member 10, and a novel double acting spring device B including a rod 11 connected at one end to the member 10, means including a barrel 12 rigidly connecting the switch points 8 and 9 and having the rod 11 slidably extended therethrough, a movable abutment 13 secured on the rod 11 and slidable in the barrel 12, and springs 14 and 15 coacting with the barrel 12 and the abutment 13 to yieldingly resist relative move-

ment between said barrel and the rod 11 in opposite directions. The arrangement is such that when the switch point 8 is moved against the rail 5, the spring 14 is compressed to yieldingly resist separation of switch point 8 from rail 5 and to return said switch point into contact with said rail if there should be any forcible separation due to passage of a locomotive or train through the switch when the latter is set against said locomotive or train. Also, when the switch point 9 is moved against the rail 6, the spring 15 is compressed to act the same way relative to said switch point 9. In either case, the active switch point may yield to avoid damage to the switch or derailing of the locomotive or train.

Centrally apertured fixed abutments 16 are secured in the opposite ends of barrel 12 by means of bolts 17 which pass downwardly through said barrel and into said abutments 16. Bearing bushings 18 for rod 11 are provided in the central apertures of abutments 16, and the springs 14 and 15 encircle rod 11 at opposite sides of movable abutment 13 and between the latter and abutments 16. The switch points 8 and 9 are disposed on spaced seats 19 provided on the top of barrel 12, and the bolts 17 are connected by a tie-bar 20. Clamping plates 21 are disposed on the bolts 17 beneath the ends of bar 20, and nuts 22 are threaded onto bolts 17 above the bar 20 and act to draw the clamping plates 21 down against the base flanges of switch points 8 and 9 to securely fasten the barrel 12 to the latter for movement therewith.

As shown, the device A may consist of a support 23 secured on a long one of the ties 7 and having spaced ears 24 in which are secured the ends of a guide rod 25. A sleeve 26 is slidable on guide rod 25 and has the member or angular arm 10 fixed thereto. A lever 27 is pivoted at one end as at 28 to the support 23. Adjacent its pivoted end, the lever 27 has a crank pin 29 that projects into a vertically elongated slot 30 provided in a lug 31 projecting upwardly from sleeve 26. The arrangement is such that when lever 27 is swung to the position shown, switch point 9 is pressed against rail 6, and when lever 27 is swung to the left of Figure 3, switch point 8 is pressed against rail 5. In either position of lever 27, pin 29 passes to a position slightly lower than pivot 28 so as to lock the switch in the position to which it has been thrown.

In Figure 1, the switch is shown set to complete the side track. Should a locomotive or train pass to the right through the switch when it is so set, switch point 9 will yield away from

rail 6 due to the fact that the switch points and barrel B are allowed to move laterally of the track by the spring 15 which is then compressed and acting to press the switch point 9 into engagement with rail 6. In this way, damage to the switch and derailing of the locomotive or train is prevented. Also, after the locomotive or train passes through the switch, the spring 15 acts to again press the switch point 9 against the rail 6. The same action will take place if switch point 8 is pressed against rail 5 to complete the main track and a locomotive or train should pass through the switch from the side track onto the main track. In the latter event, spring 14 would allow yielding of switch point 8 away from rail 5, and would again press switch point 8 against rail 5 after passage of the locomotive or train through the switch.

From the foregoing description, it is believed that the construction, operation and advantages of the invention will be readily understood and appreciated by those skilled in the art. The device may be readily installed and operatively connected to an ordinary switch stand already in use. Minor changes in details of construction are contemplated, such as fall within the scope of the invention as claimed.

What I claim is:

1. In a railway switch, in combination, a barrel adapted to be disposed transversely of and beneath movable switch points, means to secure said barrel to movable switch points when so disposed, spaced end abutments secured in the ends of said barrel, the means to secure the barrel to the switch points including a pair of clamping plates, a tie bar, bolts extending through the clamping plates and the tie bar and securing the end abutments in the barrel, and nuts threaded on said bolts for drawing the clamping plates against the switch points, a rod extending through said end abutments axially of the barrel and having an intermediate abutment secured thereon between said end abutments, said end abutments being slidable on said rod, compression springs encircling said rod within the barrel, one of said springs being arranged between each end abutment and the intermediate abutment so that said springs yieldingly resist movement of the barrel

in opposite directions relative to said rod, and means to connect one end of said rod to means for throwing switch points to and locking the same in either main track or side track position.

- 5 2. In a railway switch, in combination, a barrel adapted to be disposed transversely of and beneath movable switch points, means to secure said barrel to movable switch points when so disposed, spaced abutments secured in the ends of said barrel, a rod extending through said end abutments axially of the barrel and having an intermediate abutment secured thereon between said end abutments, said end abutments being slidable on said rod, compression springs encircling said rod within the barrel, one of said springs being arranged between each end abutment and the intermediate abutment so that said springs yieldingly resist movement of the barrel in opposite directions relative to said rod, and means to connect one end of said rod to means for throwing switch points to and locking the same in either main track or side track position, the means to secure the barrel to switch points including spaced seats for switch points on the top of said barrel, bolts extending through said seats, a tie bar connecting said bolts, switch point clamping plates disposed on said bolts beneath the ends of said tie bar, and nuts threaded on said bolts above the tie bar for drawing the clamping plates against the bases of the switch points so as to secure the barrel to the latter.
- 10 3. The construction defined in claim 2, wherein said bolts act to secure the end abutments in the barrel, said end abutments having central apertures through which said rod extends, and bearing sleeves for said rod mounted in the apertures of said end abutments.

MARVIN E. BLYTHE.
